UNITED STATES PATENT OFFICE.

WILLIAM S. HIETT, OF MCFALL, ALABAMA, ASSIGNOR, BY DIRECT AND MESNE ASSIGNMENTS, OF THREE-FOURTHS TO WILLIAM A. FARRELL, OF MCFALL, ALABAMA, AND ONE-FOURTH TO ROSS BLACKMON, OF ANNISTON, ALABAMA.

PLOW.

1,118,933.

Specification of Letters Patent.

Patented Dec. 1, 1914.

Application filed June 5, 1913. Serial No. 771,927.

To all whom it may concern:

Be it known that I, WILLIAM S. HIETT, citizen of the United States, residing at McFall, in the county of Calhoun and State of Alabama, have invented certain new and useful Improvements in Plows, of which the following is a specification.

This invention relates to an improvement in plows.

10 The primary object of the invention is to provide a plow in which the plow standard may be conveniently adjusted to dispose the plow at various angles, and in which the adjustment may be secured without detaching the standard.

15 A further object of the invention is to provide a construction in which the beam and the supporting structure for the standard may be conveniently assembled, and which, 20 while permitting the standard to be readily adjusted, will be as substantial as the usual form of non-adjustable plow.

25 For a full understanding of the invention, reference is to be had to the following description and accompanying drawing, in which:—

30 Figure 1 is a perspective view of the plow with the various parts thereof in operative assembled relation to each other. Fig. 2 is a disassembled perspective view of the plow standard and its supporting means. Fig. 3 is a detail view showing, partly in section, the rack bar and block by which the standard is held in adjusted position. Fig. 4 is 35 a detail perspective view of the plates which are secured to the plow beam and which serve to pivotally support the plow standard in the desired relation to the beam.

40 Corresponding and like parts are referred to in the following description and indicated in all the views of the accompanying drawing by the same reference characters.

45 In the drawing, 10 designates the plow beam which is curved as at 11, the terminal 12 being curved again as at 13 to form an extension 14 which is curved as at 15, thereby providing a crotch 16. This beam may be constructed of wood, although the same is preferably formed of metal.

50 A supporting plate or arm 17 is secured to each side of the beam, said plate conforming to the shape of the beam from the point 18 to the point 12. These plates 17 are secured to the beam by bolts 19 which pass

through the beam, and their terminals 20 55 which extend beyond the beam, being pressed together as at 21. To the extreme rear terminal of the plow beam are bolted or otherwise secured a pair of plow handles 24 which may be of any desired construction 60 as regards their general outline. However, these handles differ from the ordinary handle in that they are provided on their inner faces and adjacent their lower terminals with recesses which are adapted to receive 65 the fork arms of a rack bar to be hereinafter described. The foregoing description will be readily appreciated when reference is had to Fig. 1.

The plow standard consists of a plurality 70 of spaced plates 25 which are recurved longitudinally. A plate 25 is arranged on each side of the beam, a pivot pin 26 passing through the plates and the terminals of the arms 17, the plates thus being pivotally supported on the lower terminals of said arms. 75 The plates are secured together adjacent their upper terminals 27, a spacing block 28 being disposed between the plates. A feed screw 29 passes through the spacing block 80 28. A second block 30 is disposed in spaced relation vertically with respect to the block 28, the face 31 of said block 30 being serrated. A curved rack bar 32 is disposed between these blocks, the blocks being spaced 85 sufficiently to allow for movement of the rack bar, whereby it may move over the serrations of the block 30. The terminal 33 of the rack bar is bifurcated, the bifurcations 34 embracing the portion 14 of the beam, 90 and extending within the recess 23. A pivot bolt 25 passes through the handles 24, member 14 and members 34. A coiled spring 36 is supported by the handle at 37, said coiled spring being connected at 38 with the 95 rack bar, normally maintaining the rack bar in contact with the block 28.

It will be noted that when it is desired to lock the rack bar against movement, the feed screw 29 may be moved in contact with 100 said bar, thereby forcing the teeth of said bar in contact with the serrated face 31 of the block 30. When it is desired to adjust the plow standard, the screw 29 is brought out of contact with the rack bar, the spring 105 36 drawing the bar away from the serrated face of the block 30. The plates 25 which constitute the standard may be moved on

the teeth 26, and the plow adjusted at any angle.

After the standard has been adjusted, the screw 29 is manipulated to force the teeth of the rack bar in contact with the block 30. By this construction, it will be noted that the plow may be adjusted at any desired angle, in a simple and convenient manner.

It will also be seen that the entire structure is such as may be easily and economically manufactured, and that the members which constitute the support for the plow standard form a reinforcing means for the plow beam.

15 What I claim is:—

1. A plow including a longitudinally re-curved beam, a plate arranged on each side of said beam, said plates being terminally connected, a pair of spaced plates disposed 20 one on each side of the beam and pivotally supported near the terminals of the first-mentioned plates, and means for locking the last-mentioned plates in adjusted position.

2. A plow including a longitudinally re-curved beam, a plate arranged on each side of said beam, said plates being terminally connected, a pair of spaced plates constituting the plow standard arranged one on each side of the beam, said plates being pivotally 30 supported by the first-mentioned plates, blocks arranged between the plates and in spaced relation, one of said blocks being formed with a serrated face, a screw passing through the other of said blocks, handles 35 supported on the beam, a rack bar pivotally mounted on said handle and extending between said blocks whereby the screw may be adjusted to contact with said rack bar to lock the rack bar against movement with respect to the plow standard.

3. A plow including a longitudinally re-curved beam, a plate arranged on each side of said beam, said plates being terminally connected, a plow standard consisting of a 45 pair of spaced plates, disposed one on each side of the beam, said plates being pivotally connected to the first-mentioned plates,

blocks supported in spaced relation between the second-mentioned plates, a curved rack bar one terminal of which is bifurcated, the 50 bifurcated terminal of said rack bar embracing said beam, said rack bar extending between the said blocks, and coacting means carried by the blocks for supporting the rack bar against movement.

4. A plow including a longitudinally re-curved beam, a plow standard consisting of spaced plates, disposed one on each side of the beam, means carried by the beam for pivotally supporting the plates, spaced 60 blocks interposed between the plates, the lowermost of said blocks being formed with a serrated face, a curved rack bar pivotally connected to the rear terminal of the beam and disposed to extend between said plates, 65 yieldable means for normally holding the rack bar in spaced relation to the lowermost block, and means carried by the uppermost block for forcing the rack bar in contact with the lowermost block.

5. A plow including a beam, a plow standard pivotally connected to the beam and including a pair of spaced plates disposed on opposite sides of the beam, each of said plates including an intermediate straight 75 portion and terminal curved portions, and means carried by the rear terminal of the beam for holding the standard in adjusted position.

6. A plow including a beam, a standard 80 pivotally connected thereto, said standard including a pair of spaced plates disposed on opposite sides of the beam, each of said plates being bent to produce a straight intermediate portion, and curved offset terminal 85 portions, and means pivotally attached to the rear terminal of the beam for holding the standard in adjusted position.

In testimony whereof I affix my signature in presence of two witnesses.

WILLIAM S. HIETT. [L. S.]
